CHARLES WIRT, OF PHILADELPHIA, PENNSYLVANIA.

ELECTRIC-LIGHTING APPARATUS.

1,321,864.

Specification of Letters Patent.

Patented Nov. 18, 1919.

Application filed July 23, 1915. Serial No. 41,430.

To all whom it may concern:

Be it known that I, CHARLES WIRT, a citizen of the United States, residing in the city of Philadelphia, State of Pennsylvania, have invented certain new and useful Improvements in Electric-Lighting Apparatus, of which the following is a specification.

My invention relates to means for regulating the amount of light given by an electric lamp, particularly an electric incandescent lamp, by controlling resistance in the lamp circuit.

My invention relates to means of the character referred to and comprising a simple compact piece of apparatus suitable for holding or receiving the electric lamp and having associated therewith means for regulating the same and for effecting convenient support of the entire mechanism and affording electrical connection with a supply circuit.

One of the features of my invention resides in a lamp socket structure within which is disposed the regulating resistance and its controlling means, the lamp socket structure being suitable for attachment to any usual fixture without recourse to an intermediate attachment plug or the like.

My invention resides in other features hereinafter described.

For an illustration of one of the forms my invention may take reference is to be had to the accompanying drawing, in which:

Figure 1 is a vertical sectional view, some parts in elevation, of my improved apparatus on scale larger than full scale, for the sake of clearness.

Fig. 2 is a top plan view of the parts shown in Fig. 1 with the cap removed.

Fig. 3 is a top plan view of the resistance element.

Fig. 4 is a side elevational view of the brush rotating means and its support.

Fig. 5 is a bottom plan view of the parts shown in Fig. 4.

Fig. 6 is a diagrammatic view illustrating a suitable arrangement of electrical connections.

Referring to the drawing, an ordinary lighting bracket or fixture pipe 1 receives on its lower screw-threaded end the screw threaded nut 2 held within the upper end 3 of the metallic cap 4, the lower end of the nut 2 being spread over at 5 upon the washer 6 to hold it securely in place. The screw 7 serves to lock the nut 2 upon the pipe 1. The con-

ductors 8 and 9 communicating with a suitable electric supply circuit extending through the pipe 1 and through a perforation in the insulating cap lining 10 to the 60 binding posts or terminal clamps 11 and 12 secured upon the porcelain member 13 disposed within the metallic shell 14 held to the cap 4 by usual bayonet or other suitable connections. The terminal clamp 11 has a part 65 extending downwardly through an aperture 15, in block 13, said part terminating in the metallic ring 16 disposed in a ring shaped countersink in the block 13 and embracing the hollow cylindrical extension 17 on the 70 block 13. The terminal clamp 12 has the extension 18 disposed in the countersink 19 in the top of the block 1, such extension 18 having a screw threaded hole in the axis of the apparatus receiving the screw 20 which 75 extends through the boss 17 and block 13, such screw 20 holding the terminal 12 securely in place when the parts are assembled.

In a lateral depression 21 on the under side of the block 13 is held by the screw 22 80 the flange 23 on the chain or cord guide 24 here shown as having bell shape, and through which extend the pull cords or chains 25 and 26, the former of which extends into the tube 27 and is secured thereto in the slot 85 28 in the lower end thereof which has thereon an enlargement or ball 29. The other cord or chain 26 passes freely through the tube 27 and has attached to its lower end a ball or button 30. The cords or chains 25 90 and 26 have their other ends secured to the metallic drum 31 at points substantially diametrically opposite to each other; for this purpose the ends of the cords or chains engage in the apertures 32, 32, Fig. 4, of the 95 members 33 which extend through apertures in the drum 31, the inner ends of the members 33 being held between the drum 31 and the porcelain drum 34 to which the metallic drum 31 is secured. The drum 31 comprises 100 the cylindrical part 31 and the flange 35, the latter substantially flush with the upper surface of the porcelain drum 34 which has a lower flange 36. The drum 31 abuts against the flange 36 at its lower edge and is prevented from rising by the struck-up lugs 37 105 which are bent into apertures 38 in the member 34, holes 39 in the lower face of the flange 36 giving access for the tool which bends the lugs 37 to position illustrated. 110 Within the porcelain drum 34 is a cylindrical metallic bush 40 through which extends

the metallic sleeve 41 upon which the drum 34 is rotatable by actuation of the cords or chains 25 and 26. The upper end of the sleeve or bush 41 engages the metallic ring 16 in electrical communication with the terminal 11. Secured to the lower side of the porcelain block 34 by the washer 42 is the spring contact plate 43 in electrical connection with sleeve 41 and having struck-up 10 projections 44 engaging in depressions in the lower face of the block 34. The member 43 is cut along the lines 45 forming the projecting fingers 46, which are spring contact fingers, deflected out of the plane of the 15 main part 43.

The sleeve or bushing 41 is clamped between the ring 16 and the porcelain block 47 which has a central boss extending into the sleeve 41 and which is provided with 20 an axial perforation through which the screw 20 extends. The screw 20 extends through the metallic washer 48 and through the insulating washer 48^a to prevent contact between the washer 48 and the threaded shell 25 49 which receives the threaded base of an incandescent lamp L. This threaded shell 49 has the inturned flange 51 which has projections 52 extending into recesses in the block 47. It thus will be seen that screw 30 20 in effect holds the parts in their position, the block 18, screw 20 and block 47 being stationary or non-rotatable, as is also the screw threaded socket shell 49.

The resistance element comprises the resistance conductor 53 wound in one or more helical layers and disposed within the plastic insulating material 54 between the inner metallic shell 55 and the outer metallic shell 56. Disposed in the plastic material 54 are 35 the contact members 57, 58, 59 and 60 of which 57 is in electrical communication with the metallic shell 55 which is also in electrical communication with the screw threaded shell 49 which receives the screw threaded terminal 50 of the incandescent lamp L. One end of the resistance conductor 53 is connected to the contact member 57; the contact member 60 is connected to the other end of the resistance conductor, and the contacts 58 and 59 are connected to the resistance conductor at suitable intermediate points, the contacts 58, 59 and 60 being insulated by the plastic material 54 from the shell 55. All the contacts 57 to 60 inclusive 45 have their upper ends preferably flush with the upper end of the plastic material 54, and the spring contacts 46 in their rotation engage these contacts in succession. The resistance element is held securely within the shell 14 by any suitable means.

The cylindrical shell 14 may extend downwardly to the lower edge or below the resistance element and thus form a device which has the appearance of the usual incandescent lamp socket. As here illustrated the shell 50

14 may have a bell as 61 to constitute a shade holder having the usual shade engaging screws 62.

Connection between one supply circuit conductor, as 8, and one terminal of the lamp 70 L is made directly to binding clamp 12, member 48, screw 20, and washer 48 with which latter or the screw head the central lamp terminal engages when the lamp is screwed home in the screw threaded 75 sleeve 49.

The other supply circuit conductor, as 9, connects with the binding post or terminal clamp 11 which is integral with the ring 16, thence through said ring 16 and the sleeve 41 80 and bushing 40 with the contact fingers 46.

In the position shown in Fig. 6 no current is passing through the lamp L. If, however, one or the other of the cords 25 or 20 is pulled to bring one of the contact fingers 46 into engagement with contact 60, current will pass through the lamp L and all of the resistance 53, with the result that the lamp L will be but slightly illuminated. Upon engagement with contact 59 the first 90 section of resistance is cut out, with the result that the current through the lamp increases and it glows brighter; when a brush 46 engages contact 58 another section of resistance is cut out with resultant increase 95 in current and greater brightness of the lamp. Finally, when a brush 46 engages contact 57 all of the resistance is cut out and the lamp glows at its brightest, because it is then subjected to the full voltage of the 100 supply circuit 8, 9.

What I claim is:

1. A lamp socket comprising an immovable hollow resistance element, means within said element for supporting the base of 105 an incandescent electric lamp, an insulating member rotatable relatively to said element, and means carried by said member for cutting different amounts of resistance in circuit with said lamp.

2. A lamp socket comprising an immovable hollow resistance element adapted to surround the base of an incandescent electric lamp, said hollow resistance element containing a resistance, a rotatable switch member of insulating material associated with said element, and means carried by said switch member for connecting electrically different portions of said resistance conductor in circuit through the lamp.

3. A lamp socket comprising an immovable hollow resistance element, means for supporting the base of an incandescent electric lamp within said element, a rotatable switch member of insulating material associated with said hollow resistance member, and means for varying the amount of resistance in said hollow resistance element in circuit with the lamp.

4. A lamp socket comprising a shell for 130

- engagement with the base terminal of the lamp, a hollow resistance element surrounding the shell and immovable in relation thereto, said resistance element having a 5 resistance conductor electrically connected with the shell, means for electrically connecting said resistance conductor at points intermediate its ends, a rotary switch member of insulating material associated with 10 said hollow resistance conductor, and means associated with said switch member for conducting current through said hollow resistance element at different points thereof.
5. A lamp socket comprising a shell for engagement with the base terminal of the lamp, a hollow resistance element surrounding the shell and immovable, in relation thereto, said resistance element having a resistance conductor electrically connected 15 with the shell, a plurality of contact members electrically connected with different parts of the resistance conductor, a rotary switch member of insulating material associated with said hollow resistance element 20 and having a contact element adapted to engage with different contact members as it is rotated, means for rotating the switch member, an electrical connection with the shell, and an electrical connection with the 25 switch member.
6. The combination with a resistance element for a lamp regulator comprising separate metallic tubular members, a resistance coil disposed in plastic material between 30 said members, contacts embedded in said plastic material and communicating with different points in said resistance conductor, one of said contacts and one end of said resistance conductor connecting with one of 35 said tubular members, of means within said one of said tubular members and in electrical communication therewith for receiving a lamp, and rotatable contacting mechanism 40 adapted to engage said contacts.
- 45 7. The combination with a resistance element in the form of a hollow cylinder, of means for receiving a lamp disposed within said cylinder, two insulating members clamped together, one of said insulating 50 members disposed within said resistance element, a lamp socket terminal on said last named member, and rotatable contact mechanism coöperating with said resistance element and disposed between said insulating 55 members.
8. The combination with a stationary resistance element, a plurality of spaced insulating bodies, of a contact member carried between the insulating bodies and a 60 rotatable table relatively thereto, said contact member coöperating with said stationary resistance element.
9. The combination with spaced insulating bodies, a conductor for supporting the 65 bodies, a rotatable contact member disposed
- between the bodies and insulated from the conductor, of a lamp receiving shell secured to one of said insulating bodies, a resistance element secured to the shell, and means for rotating the member relatively to the resistance element. 70
10. The combination with two insulating bodies, means for spacing the bodies apart, devices for clamping the bodies to the spacing means, a socket adapted to receive a lamp, said socket secured to one of said bodies by means of the clamping devices, of a resistance element secured to and surrounding the socket, a member carried on the spacing means between the bodies, said member coöperating with the resistance element, and means for rotating the member relatively to the bodies and the resistance element. 75
11. The combination with two insulating bodies, a tube for spacing the bodies apart, a bolt for clamping the bodies to the tube, said bolt extending through the tube, a socket secured to one of the bodies, and adapted to receive a lamp, of an adjustable resistance 80 rigidly secured to and surrounding the socket, a drum of insulating material carried on the tube, a brush carried by the drum, and means for rotating the drum whereby the brush may coöperate with the 85 adjustable resistance. 90
12. The combination with two insulating bodies, a tube for spacing the bodies apart, a bolt for clamping the bodies to the tube, said bolt extending through the tube, a socket secured to one of the bodies, and adapted to receive a lamp, of an adjustable resistance rigidly secured to and surrounding the socket, a drum of insulating material carried on the tube, a skirt depending from 100 one of the bodies and encircling the drum, a brush carried by the drum, and means for rotating the drum whereby the brush may coöperate with the 105 adjustable resistance. 110
13. The combination with a bell shaped shell, of an annular resistance element rigidly secured to and located within the same, a lamp receiving shell rigidly secured to and within said resistance element, a switch carried between insulating members 115 within said first named shell, said switch being movable relatively to said insulating members and bell shaped shell. 120
14. A lamp socket comprising a shell for engagement with the base of a lamp, a hollow resistance element surrounding the shell and immovable in relation thereto, said resistance element having a resistance conductor electrically connected with the shell, a plurality of contact members electrically 125 connected with different part of the resistance conductor, a block, a standard electrically insulated from the shell and adapted to electrically contact with the other terminal of the lamp, said standard mechanically 130

connecting the resistance element immovably in relation to the block, a rotary switch member surrounding the standard and electrically insulated therefrom and with a contact element adapted to engage with different contact members of the resistance element as it is rotated, means for rotating the switch member, a leading-in terminal in electrical connection with the standard, and 10 a stationary leading-in terminal in electrical connection with the switch member.

15. A lamp socket comprising an inclosing shell, a fixed, hollow, cylindrical insulating element within the shell, a support 15 for an incandescent electric lamp supported

within and in immovable contact with the element, a spiral resistance embedded in the element, a rotatable cylindrical switch member of insulating material in axial alinement with the element, a spring contact carried 20 by the switch member for electrically connecting different portions of the resistance conductor in circuit with the lamp support and a spring carried by the switch member and engaging the element.

In testimony whereof I have hereunto affixed my signature this 19th day of July, 1915.

CHARLES WIRT.
